UNITED STATES PATENT OFFICE.

GEORGE R. CULLINGWORTH, OF NEW YORK, N. Y.

REGULATOR FOR AIR-COMPRESSORS.

SPECIFICATION forming part of Letters Patent No. 377,481, dated February 7, 1888.

Application filed May 18, 1887. Serial No. 238,634. (No model.)

To all whom it may concern:

Be it known that I, GEORGE R. CULLINGWORTH, of the city and county of New York, and State of New York, have invented a new and useful Improvement in Regulators for Air-Compressors, of which the following is a specification.

In connection with air-compressors employed to supply and maintain a volume of compressed air in a receiver or tank for use in operating a number of rock-drills or other machines it is common to employ a regulator which comprises a motor-piston loaded to any desired extent, and which is acted upon by compressed air from the receiver, so that when the air within the receiver exceeds the pressure which it is desired to maintain the motor-piston comprised in the regulator will be moved or lifted.

20 In my United States Letters Patent No. 287,104, dated October 23, 1883, I have shown a system of mechanical connections whereby the motor-piston of the regulator, when moved by an excessive pressure of air, acts to partially close a valve through which the engine driving the compressor is supplied with steam, so that when the pressure within the receiver exceeds that desired the supply-valve of the engine will be more or less closed to stop it

25 entirely or reduce its speed.

The object of my invention is to provide means whereby this closing of the supply-valve of the engine, which I term the "throttle-valve," shall be effected by the pressure of air; and to this end I combine with such supply or throttle valve a piston, and I also provide, in connection with the regulator motor-piston, a valve operated thereby, and which, when the motor-piston is raised or moved by an excessive air-pressure, is opened to admit air to the motor-piston of the supply-valve in order to close said supply-valve.

In the accompanying drawings, Figure 1 represents an elevation of such parts of an air-compressor as are necessary to illustrate my invention, a regulator with its valve and a valve for controlling the supply of steam to a compressing-engine with its motor-piston being shown in section. Fig. 2 is a corresponding view with the parts in a different position. Fig. 3 is a sectional elevation upon the plane

of the dotted line α - α , Fig. 1, transverse to the axis of the compressor-cylinder; and Fig. 4 is a vertical section of the regulator-motor upon a larger scale than Fig. 1.

55

Similar letters of reference designate corresponding parts in all the figures.

A designates a portion of the compression-cylinder of an air-compressor, and B designates a passage which extends from one end to the other of the cylinder, and which communicates with the opposite ends in a well-understood manner. In such passage B is a valve, B', (here shown as balanced,) and it is obvious that when this valve B' is opened there is free communication between the opposite ends of the compressor-cylinder, and the pressure in advance of the main compressing-piston is relieved by the air being passed through the passage B from one end to the other of the cylinder. Connected with the stem of the valve B' is a motor-piston, C, which is fitted within a cylinder, C', and to this cylinder, below the piston, air-pressure is supplied through a pipe, c, and a port or passage, c', from the receiver for compressed air, into which air is pumped by the operation of the main compressor. The motor-piston C is loaded to hold the valve B' to its seat, and in this example of the invention this loading is accomplished by weights 80 d, suspended by a rod, d', from a lever, d", which is fulcrumed at d", and exerts pressure through a plunger or bar, d", upon the motor-piston C.

D designates a valve shell or casing, which is to be placed in the line of steam-pipe leading to the engine which operates the compressor, and in this shell or casing is a valve, D', (here shown as balanced.) To the stem of this valve D' is connected a small motor-piston, D", operating within a suitable cylinder, D', and a pipe, D', connects this cylinder D' with the regulator. As here represented, a portion, c", of the valve-stem, which connects the motor-piston C with the valve B', is made tubular and fitted to a tubular bore, c", extending 95 from the motor-cylinder c', and this tubular stem c" constitutes a valve for controlling the flow of air under pressure from the pipe c to the pipe D', which leads to the motor-cylinder D' of the valve D'. Within the cylindric bore c", which receives the valve c", I have represented a belt, c", which communicates by a

port or passage, c^8 , with the pipe D^4 , and in the wall of the tubular stem c^2 I have represented openings c^5 c^6 c^7 . When the valve D' is opened, as shown in Fig. 1, and the pressure within 5 the receiver is not excessive, the motor-piston C , by reason of the weight with which it is loaded, remains in its lowest position, closing and holding the valve B' closed. In this position of parts the port or passage c^7 is exposed 10 below the valve-casing c^3 , and the port or passage c^5 in the hollow stem c^2 is opposite the port or passage c^8 . Consequently the cylinder D^3 has a free air-vent through the pipe D^4 , the passage c^8 , the hollow stem c^2 , and the opening c^7 , and the valve D' is fully opened. 15

When the pressure within the receiver for compressed air exceeds that desired, the compressed air passing through the pipe c and the passage c' to the cylinder C' lifts the motor-piston C , thereby opening the valve B' , and places opposite ends of the compressor-cylinder A in free communication through the passage B . By this movement of the motor-piston C the opening c^5 is raised above the valve-casing 20 c^3 and is exposed in the cylinder C' , and at the same time the opening c^7 is sheathed within the valve-casing c^3 , this being the position of parts shown in Fig. 2. The compressed air may therefore pass through the cylinder C' , 25 through the opening c^5 , to the hollow stem c^2 , and thence through the opening c^6 and the port c^8 , and through the pipe D^4 to the cylinder D^3 . In the cylinder D^3 the compressed air acts upon 30 the piston D^2 and serves to close the valve D' , thereby diminishing or cutting off the supply 35 of steam to the operating-engine for the time being. As soon as the pressure of air within the receiver falls to or below the normal pressure, the motor-piston C , by reason of its load, descends, closing the valve B' and placing the 40 parts in the position shown in Figs. 1 and 4, thus permitting the valve D' to open and the operating-engine to resume its work.

The ports and passages above described will 45 be more easily located and their function more readily understood from Fig. 4, in which the position of parts corresponds with Fig. 1, but which is upon a larger scale.

What I claim as my invention, and desire to secure by Letters Patent, is—

1. The combination, with a valve for controlling the supply of steam for operating an air-compressor and an actuating-piston connected with said valve for closing it, of a valve for relieving the pressure before the main 55 compressor-piston, a motor-piston connected with the relief-valve and arranged to be acted on by compressed air, and a valve operated by the motor-piston and serving when opened to admit compressed air to act upon the actuating-piston of the supply-valve for closing said supply-valve, substantially as herein described.

2. The combination, with a valve for controlling the supply of steam for operating an 65 air-compressor and an actuating piston connected with said valve for closing it, of a valve for relieving the pressure before the main compressor-piston, and a motor-piston connected with said relief-valve and arranged to be acted 70 on by compressed air, and having a hollow rod which serves as a valve for admitting air to act upon the actuating-piston of the supply-valve for closing said valve, substantially as herein described.

3. The combination, with the steam supply valve D' and its actuating piston and cylinder D^2 D^3 , of the passage B , for connecting the ends of a compressor-cylinder, the relief-valve B' in said passage, the motor-piston and its hollow 80 rod C c^2 , connected with the relief-valve B' and having the passages c^5 c^6 , and the cylinder and cylinder-extension C' c^3 for said motor piston and rod, and having the passages c^7 c^8 and the pipes c D^4 , for supplying compressed air to the 85 motor-cylinder C' and for conducting compressed air from the passage c^8 to the actuating-cylinder D^3 of the valve D' , substantially as herein described.

G. R. CULLINGWORTH.
